ABSTRACT OF THE DISCLOSURE

A system is disclosed for serving station-to-station customer dialed coin calls on a wholly automatic basis without any operator intervention being required either for notifying the calling party of the monetary deposits required or for monitoring the collection of the required charges. A system controller is provided for deriving call charge information and for controlling an announcement apparatus which transmits the derived charge information to the calling station. The tones generated at the calling station as coin deposits are made are detected by a special receiver and transmitted to the system controller which then determines whether the amount deposited corresponds to that requested by the announcement apparatus.

This invention relates to a switching system, and more particularly to a switching system having improved facilities for serving customer-dialed toll calls originating at coin pay stations. This invention further relates to a switching system in which equipment is provided for automatically performing the functions that heretofore required operator intervention on customer-dialed station-to-station coin toll calls. This invention still further relates to a telephone system which, during the serving of calls of the foregoing type, automatically transmits an announcement containing time and charge information to a calling coin station, monitors the coins deposited by the calling party, and determines whether the amount deposited equals the amount requested in the announcement.

Recent improvements in the field of telephone switching permit an increasing percentage of toll calls to be completed on a customer-dialed basis. These improvements permit customer-dialed calls to be served, depending on their type, either without any operator assistance whatsoever, or with a substantial reduction in the quantity of operator assistance compared with that heretofore required. For example, a substantial percentage of all customer-dialed noncoin station-to-station toll calls may now be completed without operator assistance. Also, the recently introduced person-to-person type systems permit calls such as person-to-person, collect, charge-to-third party, etc., to be completed on a customer-dialed basis from noncoin stations with operator assistance being required only for the furnishing of the service required above and beyond the completion of a connection to the called station.

The copending L. J. Cerny et al. application, Ser. No. 325,842, filed Nov. 26, 1963, now Patent 3,341,662, issued Sept. 12, 1967, and the R. J. Jaeger, Jr. et al application, Ser. No. 519,787, filed Jan. 10, 1966, disclose equipment which permits both station-to-station and person-to-person type calls originating at coin pay stations to be served on a customer-dialed basis. In accordance with the systems disclosed in each of these applications, operator assistance is required on station-to-station coin calls for the purpose of transmitting time and charge information to the calling party and for monitoring the deposit of the requested charges. The time and charge information re-

2

laid by the operator is automatically derived by a system controller and displayed at the operator's position. On person-to-person type coin calls, operator assistance is required for the same reason as on the station-to-station type, as well as for additionally providing the services required above and beyond the completion of a connection to the called station.

The operator assistance provided on person-to-person calls is of such a varied personal and specialized nature that, at the present state of the art, it cannot be readily automated. On the other hand, the services performed by the operator on station-to-station coin calls are, for the most part, routine, since her sole function on these is (1) to relay to the calling station the time and charge information that has been automatically derived and displayed at her position and (2) to monitor the collection of the requested charges from the tones generated at the calling coin station in response to each coin deposit.

A large percentage of all customer-dialed toll calls originating at coin stations are of the station-to-station type and, thus, the elimination of the need for operator intervention on these would be most desirable in terms of economies of operation and improved customer service. Operator assistance would then be required on only a relatively small percentage of coin toll calls, i.e., those of the person-to-person type.

It is therefore an object of the invention to provide improved facilities for serving customer-dialed station-to-station coin toll calls.

It is a further object to provide facilities which permit customer-dialed station-to-station coin toll calls to be completed without operator intervention.

It is a further object of the invention to automate the serving of calls of the foregoing type by the provision of equipment which performs the call-serving functions that heretofore required operator intervention.

In accordance with the specific disclosed illustrative embodiment of the invention, equipment is provided which permits customer-dialed station-to-station coin toll calls to be completed without operator intervention. This equipment comprises (1) recorded announcement apparatus which automatically transmits time and charge information to a calling coin station, and (2) apparatus which utilizes the tones generated at the calling station in response to each coin deposit to determine whether the amount deposited matches the amount requested. The announcement and the coin deposit monitoring equipment may be utilized at the beginning of a call for the collection of the initial period deposit, at the beginning of each overtime period for the collection of interim overtime charges and, upon the termination of a call for the collection of post-pay overtime charges.

The invention is shown embodied in a system of the type disclosed in the aforementioned Jaeger-Joel specification. Jaeger and Joel disclose equipment which provides various types of call service on calls incoming to a toll office from the local offices it serves on an originating basis. The Jaeger-Joel system is not a switching system, per se; it does not comprise a portion of either the toll or local offices; and it is situated intermediate the toll office and the local offices. The Jaeger-Joel equipment is typically referred to as a traffic service position system (TSPS) since it is independent both geographically and equipmentwise of any existing office and since its sole function is to provide call service on many types of calls incoming to the toll office. The TSPS center is designated in this manner, rather than as a switching system, since it performs no switching operations whatsoever in connection with the selection of a route or trunk that is to be utilized in extending a call from a local to a toll office.

The equipment provided at the TSPS center includes

operator positions, charge data recording apparatus, call-timing facilities, together with apparatus for temporarily connecting operator positions to calls requiring assistance for their completion. Each call extended via the TSPS center to a toll office is monitored and timed and, if desired, pertinent charge data therefor is recorded upon the call termination. If the call requires operator assistance, a connection within the TSPS center to an operator is established at the same time the forward connection is being set up by the toll office. Once connected, the operator performs the call duties required of her and then depresses keys at her position to indicate the type of service provided and to release her position from the connection. This leaves the calling and called stations connected, speechwise, for the call duration.

The installation of the Jaeger-Joel TSPS equipment in an existing telephone network enables it to serve many additional types of calls with little or no modifications being required at either the local or toll offices. Included in the types of calls that may be then served by the resultant system, once the TSPS center is incorporated as a part thereof, are: (1) noncoin customer-dialed person-to-person type calls for which the TSPS center provides the operator assistance required above and beyond the completion of the connection to the called station, (2) non-coin customer-dialed station-to-station toll calls for which the TSPS center performs a timing and charge data recording operation, (3) customer-dialed station-to-station coin toll calls for which the TSPS equipment derives the applicable time and charge information and transmits it to an operator (the operator, in turn, orally relays the information to the called station and monitors the collection of the required charges), and (4) customer-dialed coin persons-to-person type calls which are served in the same manner as coin station-to-station calls except that, in addition, the operator must provide the service required on noncoin person-to-person type calls.

The equipment provided in accordance with my invention at the TSPS center includes recorded announcement apparatus comprising, for example, a plurality of magnetic tape mechanisms, a plurality of separate tracks on a magnetic drum, or any other suitable apparatus by means of which different recorded announcements may be made available upon selection for transmission back to a calling station. In accordance with a first alternative embodiment of the announcement apparatus, each track may contain an entire message representing a unique combination of time and charge parameters. The announcements on the plurality of tracks together are capable of providing time and charge information for any call served by the TSPS center. The announcement apparatus may alternatively comprise a plurality of recorded tracks, each of which contains an elemental portion of a message. Each message transmitted to a calling station is synthesized by connecting the call to a plurality of tracks sequentially in a required timed relationship.

Upon the arrival of a coin station-to-station toll call at a TSPS center equipped in accordance with my invention, called and calling station information is received from the local office and registered in the TSPS system controller as disclosed by Jaeger-Joel. The initial period time and charges are derived by the controller in response to the registration of the calling and called station information as well as in response to information available within the TSPS system itself, such as for example, the time of day, etc. After this information is derived, a temporary connection at the TSPS center is established between the incoming call and the announcement apparatus. The controller then controls the operation of the announcement apparatus so that it transmits a message to the calling party advising him of the applicable initial period time and charges, such as for example, 60 cents for three minutes.

It is known in the art to equip coin stations with coin collection apparatus which emits audible signals signifying

the amount of coins deposited. In particular, coin collection apparatus has recently been introduced which has only a single slot for the acceptance of all coins, with the deposit of each type of coin causing a series of tone pulses to be generated. The number of pulses generated for each coin deposit is equal to the number of nickels in the deposit, i.e., one pulse for 5 cents, two pulses for 10 cents, and five pulses for 25 cents. Patents which disclose coin collection apparatus of this type are 3,146,312 to E. R. Andregg, et al. of Aug. 25, 1964; 3,170,039 to E. R. Andregg, et al. of Feb. 16, 1965; 3,116,370 to E. R. Andregg, et al. of Dec. 31, 1963.

The equipment I provide at the TSPS center further includes a coin tone receiver which detects the tones generated by the calling station in order that the system controller may determine whether the amount deposited matches that requested in the recorded announcement. Following the transmission of the recorded announcement to the calling station, the TSPS switching network disconnects the call from the announcement apparatus and connects it to an idle coin tone receiver. The receiver detects the coin tones generated at the calling station and transmits signals to the system controller signifying the receipt of each coin tone pulse. The system controller counts the coin pulses and determines whether the calling party has deposited the requested initial period charge.

If the amount deposited by the calling party is either less or more than the amount requested, the call is routed to an available operator position where it is served in the manner described in the Jaeger-Joel specification. If the amount deposited equals the amount requested, the coin tone receiver is disconnected and the system controller effects the remaining operations required on the call at the TSPS center. As described in Jaeger-Joel, these include the connection of the call to an outpulser which transmits to the toll office the information it requires for the extension of the connection to the terminating office and called station. The outpulser is then disconnected and the parties may converse after the called station answers.

Each call is automatically timed by the system controller. If the call now being described is terminated before the initial period elapses, the appropriate data for the call is recorded and the TSPS circuits serving the call are restored to an idle condition, as disclosed by Jaeger-Joel. Two different procedures are commonly utilized to collect the overtime charges for those coin calls which extend into overtime. In accordance with one procedure, the charges are collected on an advance basis at the beginning of each overtime interval. With the second procedure, the charges are collected on a postpay basis at the termination of the call.

If the first overtime collection procedure is utilized, the system controller (1) detects the termination of the initial period, (2) derives the time and charge for a single overtime period, (3) connects the call to the announcement equipment, (4) controls the operation of the announcement equipment so that it transmits a message signifying the duration of the overtime period and the amount of charge that must be deposited at this time, (5) disconnects the call from the announcement apparatus and (6) connects it to a coin tone receiver which monitors the collection of the requested charge and transmits an indication thereof to the system controller. The coin tone receiver is subsequently disconnected if the calling party deposits the requested amount, and the parties are then free to converse for the duration of the overtime period. If the deposit is less or more than the requested amount, the call is connected to an operator position. This collection procedure is repeated at the beginning of each subsequent overtime interval for the duration of the call.

If the second procedure is used (the collection of overtime charges on a postpay basis), the system controller, upon the termination of the initial period, connects the call to the announcement equipment which (1) informs the calling station that the initial period has ended and

that the call is entering overtime, (2) advises the calling party of the charge and duration of a single overtime period, and (3) requests that he flash his switch hook upon the termination of the call. The announcement apparatus is then disconnected and the overtime portion of the call is timed by the system controller. Upon the call termination, the system controller (1) computes the chargeable overtime and the overtime charges, (2) connects the call to the announcement equipment, (3) disconnects the announcement equipment after the required announcement has been generated and transmitted to the calling station, and (4) connects the call to a coin tone receiver which monitors the collection of the requested overtime charges in a manner similar to that already described for the collection of initial period charges.

It may be seen from the foregoing that my invention eliminates the necessity of operator service on most station-to-station coin DDD calls and thereby contributes to improved operating efficiencies and improved customer call service.

A feature of the invention is the provision of announcement apparatus which, in response to the receipt of calling and called station information on customer-dialed coin calls, automatically transmits to the calling station an announcement containing time and charge information including the monetary amount that is to be deposited as call charges.

A further feature of the invention is the provision of equipment for automatically determining whether the amount deposited at the calling station matches that requested in the announcement.

A further feature is the provision of equipment responsive to a determination that the proper amount was deposited at the calling station for controlling the completion of a connection to the called station.

A still further feature is the provision of equipment for monitoring and timing the call following an off-hook condition at the called station and for automatically transmitting an announcement to the calling station upon the call termination indicating additional time and charge information pertaining to that portion of the call extending beyond the period for which the charges were initially paid.

It is another feature to provide in a call service center, located intermediate a toll and a local office, equipment which is responsive to the receipt of calling and called station information on customer-dialed coin calls for deriving initial period time and charge information, equipment which automatically transmits an announcement containing this information to the calling station, equipment which monitors coin deposit signals generated at the calling station in response to coin deposits thereat, equipment which is responsive to the coin deposit signals for determining whether the amount deposited at the calling station matches that requested in the announcement, and equipment which controls the completion of a connection through the toll office to the called station in the event that the proper amount is deposited at the calling station.

It is still another feature to provide in the call service center equipment for monitoring and timing the call following the off-hook condition at the called station, equipment effective upon an on-hook condition at either the called or calling station for determining the total charge for the call, and equipment operative in the event that additional charges are due beyond those already deposited for automatically transmitting an announcement to the calling station indicating additional time and charge information, including the additional charges due.

These and other objectives, advantages, and features of the invention may be more readily understood upon a reading of the following description of an exemplary illustrative embodiment thereof taken in conjunction with the drawing in which:

FIG. 1 discloses a block diagram embodiment of the invention;

FIGS. 2A, 2B, and 2C, when arranged as shown in FIG. 3, diagrammatically disclose additional details of the invention;

FIGS. 4 and 5 disclose an MF trunk circuit;

5 FIGS. 6 and 7, when arranged as shown in FIG. 8, disclose a coin control trunk circuit;

FIG. 9 discloses a coin tone receiver;

FIGS. 10, 11, and 12A through 12D, when arranged as shown in FIG. 13, disclose a stored program controller (SPC); and

10 FIGS. 14 and 15 disclose two separate embodiments of my announcement apparatus.

Block diagram—FIG. 1

15 FIG. 1 diagrammatically discloses my invention in a manner which facilitates an understanding of its broader aspects. The invention is shown as embodied in the system disclosed in the aforementioned Jaeger-Joel specification, which is hereby incorporated as part of the present application to the same extent as if fully disclosed herein. Shown on FIG. 1 is a TSPS center 100 which is interconnected between the local offices 101A and 101B and toll office 102. The TSPS center contains a plurality of trunk circuits 103-1 through 103-n, each of which is connected on its incoming side to a corresponding one of local office outgoing trunk circuits 120A-1 through 120B-n and on its outgoing side to a corresponding one of toll office incoming trunk circuits 121-1 through 121-n. With this arrangement, each outgoing trunk circuit at the local office is individual to a different one of the TSPS trunk circuits 103- and, in turn, to a different one of the toll office incoming trunk circuits 121-. Each call from a local office is extended via a selected outgoing trunk circuit 120- to its associated TSPS trunk circuit, and, in turn, to its associated incoming toll trunk circuit.

20 The TSPS center further includes a switching network 104, which is connected on its left side to trunk circuits 103- and on its right side to various other circuits, such as for example, outpulsers 106, digit receivers 107, position buffers 108, coin tone receivers 150, announcement equipment 152, and miscellaneous other circuits which, for the purpose of this figure, are represented generally as miscellaneous tone and service circuits 117. Switching network 104 includes link 104A, which contains 25 the circuit paths required to interconnect the circuits having left side network appearances with those having appearances on the right side of the network. The network 104 further includes network controller 104B, which controls the operation of the link in its path-establishing function.

30 TSPS 100 further includes a system controller (system control 105), which is connected by cable 113 to trunk circuits 103-; by cable 116 to controller 104B; by cable 115 to recorder 114; by cable 111 to outpulsers 106, digit receivers 107, and service circuits 117; by cable 112 to position buffers 108; by cable 122 to positions 35 109-, and by cable 128 to the coin tone receivers 150 and the announcement equipment 152. These connections permit the system control to regulate, control, and coordinate the operation of each circuit in order that the TSPS center may furnish the service required of it on each call.

35 Each TSPS trunk circuit 103- is connected by means of two separate conductor pairs to two separate link appearances on the left side of link 104A. Conductor pair T and R connects the incoming side of the trunk circuit to the link. This permits the circuits on the right side of the link to communicate with the local office. The T1 and R1 conductor pair connects the outgoing end of the trunk circuit to the left side of the link. This permits the circuits on the right side of the link, such as for example, outpulsers, to communicate with the toll office.

40 Digit receivers 107 receive call information outpulsed from a local office on each call served by the TSPS center.

45 70 75 These receivers may be of different types, such as for

example, DP or MF, depending upon the mode of outpulsing utilized. Outpulsers 106, which advantageously may be of the MF type, transmit to the toll office the information it needs on each call. AMA recorder 114 records pertinent charge data upon the termination of a call in response to information received from system control 105.

The TSPS center functions to extend a connection from a calling local office outgoing trunk circuit to its related toll office incoming trunk circuit via the TSPS trunk circuit 103- common to the local and toll office trunk circuits. The TSPS center furnishes the call services required of it simultaneously with the extension of the connection to the toll office. This service may include the recording of call charge data by recorder 114. This service may further include the attachment of an operator position 109- to the calling TSPS trunk circuit, via the link, if operator assistance or intervention is required for any reason. The operator position is disconnected from the call when the required assistance has been furnished. The calling and called stations remain connected via the TSPS trunk circuit for the call duration. The system control monitors and times the call and, upon its termination, causes recorder 114 to perform a charge data recording operation.

In order to illustrate the operation of my invention as shown on FIG. 1, let it be assumed that a customer-dialed coin call of the station-to-station type originates at coin station 119 served by local office 101A. Let it further be assumed that this call requires a routing to toll office 102 via the TSPS center. Finally, let it be assumed that in serving this call, local office 101A selects outgoing trunk circuit 120A-1. The seizure of this outgoing trunk circuit generates a signal which is received by TSPS trunk circuit 103-1 and transmitted to system control 105 over cable 113. System control responds and commands controller 104B to establish a network connection between the T and R conductors of trunk circuit 103-1 and digit receiver 107. The digit receiver receives the calling and called office information outpulsed from the local office and transmits it to system control over cable 111. System control signals controller 104B to break down the connection to the receiver when the local office outpulsing has been completed.

System control determines that the call is of the customer-dialed coin station-to-station type from the received call information and devices time and charge information applicable to the call, including the duration and charge for the initial period. The announcement equipment contains the facilities required for providing recorded time and charge information for any call served by the TSPS center. As already mentioned, this equipment may comprise either a plurality of recorder tracks, each of which contains the entirety of a message, or alternatively, it may comprise announcement tracks containing less than a complete message per track together with equipment for synthesizing any message by connecting a call to a plurality of tracks sequentially in a required timed relationship. The announcement equipment is connected over conductors 153-1 through 153-n to right side link appearances.

After system control 105 derives the initial period time and charge information, it causes the T and R conductors of trunk circuit 103-1 to be connected via the network to the announcement equipment. The operation of this equipment is controlled, by signals transmitted over cable 128, so that the required message is transmitted via the switching network trunk circuit 103-1 and local office 101A back to the called customer coin station 119. This message might, for example, request the calling party to deposit 60 cents for three minutes.

The network controller disconnects the T and R conductors of trunk circuit 103-1 from the announcement equipment following the transmission of the selected message to the calling station. It then connects these conduc-

tors to an idle coin tone receiver 150. The coin tone receiver 125 comprises frequency selective circuits and detectors which provide an output signal in response to the reception of each coin tone pulse. Following its connection to the TSPS trunk circuit, the coin tone receiver detects each tone pulse received from the calling station and transmits an indication of the reception of each pulse to system control. System control registers and counts the pulse indications and determines whether the amount deposited matches the initial period charge the calling party was requested to deposit. If the amount deposited matches that requested, the call is completed as subsequently described. If the amount deposited is greater or less than the requested amount, the T and R conductors of the TSPS trunk circuit are connected to a right-hand network appearance of an idle operator position 109- over cable 110-. The remainder of the call is then served in the manner disclosed in the Jaeger-Joel specification.

At the same time the announcement equipment and coin tone receivers are being utilized in connection with the initial period deposit collection, system control proceeds with the completion of the forward connection by causing the network controller to establish a network connection between outpulser 106 and the T1 and R1 conductors of trunk circuit 103-1. Once this connection is established, the outpulser transmits call information forward to the toll office which, in turn, controls the establishment of the forward connection to the terminating office in the normal manner. The outpulser is disconnected by the link from the calling connection upon the termination of outpulsing. The timing of the outpulsing operation is controlled so that the operations within the TSPS center associated with the collection of the initial period charges are completed by the time the ringing of the calling station takes place. At this time, assuming the proper charges are deposited, all of the priorly established link connections between the T and R and the T1 and R1 conductors of trunk circuit 103-1 will have been broken down. The calling and called stations remain interconnected by the TSPS trunk circuit at this time for the duration of the call. System control monitors and times the call by means of its interconnections 113 with trunk circuit 103-1.

It has been assumed that the initial period duration applicable to this call is three minutes. Therefore, at the end of three minutes, system control causes the link to interconnect the T and R conductors of trunk circuit 103-1 with the announcement equipment, which informs the calling party that the initial period has elapsed and that the call is now entering overtime. Also, in the same manner as is current practice for operators in most areas, the announcement requests the calling party to flash his switch hook upon the termination of the call. The link disconnects the announcement equipment from the call on the conclusion of this message and the call is then timed and monitored for the duration by system control.

The termination of the call is detected by system control, which then (1) computes the chargeable overtime, (2) computes the overtime charges due, (3) selects the announcement track or tracks containing the message applicable to the computed overtime duration and charges, (4) connects the T and R conductors of trunk circuit 103-1 to this selected track or tracks, (5) controls the operation of the announcement equipment so that the required message on the selected track is conveyed to the calling station, (6) disconnects the trunk from the announcement equipment and connects it to a coin tone receiver, and (7) counts the coin tone pulses received by the coin tone receiver to determine that the required overtime charges are deposited. The TSPS trunk circuit is then disconnected from the coin tone receiver and restored to an idle condition for the serving of another call.

The preceding description assumed that the overtime charges were collected on a postpay basis. The operation of the call was described in this manner since this is the method by which the overtime charges for coin toll calls

are usually collected. However, another method which is currently utilized, although less widespread, is for the overtime charges to be collected on a prepaid basis at the beginning of each overtime interval. The operation of the system of FIG. 1 for the collection of overtime charges in this manner is analogous to that already described, namely, the TSPS trunk circuit serving the call is connected first to the announcement apparatus and then to the coin tone receiver at the beginning of each overtime period so that the calling party may deposit the charge for a single overtime period.

Detailed description—FIGS. 2A through FIGS. 2D

FIGS. 2A through 2C, when arranged as shown in FIG. 3, disclose additional details of the embodiment of the invention shown on FIG. 1. Each element on FIGS. 2 corresponding to an element on FIG. 1 is designated in a manner to indicate the correspondence. Thus, local office 201A on FIG. 3 corresponds to local office 101 on FIG. 1, etc. Whenever such a one-for-one correspondence is possible, each such element on FIGS. 2 also has, inside the rectangle representing the element, parentheses enclosing the numerical designation of the corresponding element on FIG. 1. However, a one-for-one correspondence between each element on FIGS. 2 and FIG. 1 is not always possible, since FIGS. 2 are considerably more detailed and contains many elements which are not separately shown on FIG. 1.

The embodiment of FIGS. 2 is similar to that of FIG. 1, in that it discloses a local office 201A having an outgoing trunk circuit 220A extending via TSPS trunk circuit 203 to an incoming trunk circuit 221 and a toll office 202. Only one such interconnection between a local and a toll office is shown in order to minimize the complexity of the drawing and to facilitate an understanding of the invention. Network 204 comprises a two-stage network having a trunk link 204A and a position link 204B, together with link controllers 204C and 204D. The two links together function to interconnect TSPS trunk circuits having trunk link appearances with the service circuits having appearances on the right side of the position link. The service circuits are shown in greater detail than on FIG. 1 and comprise outpulsers 206, digit receivers 207, coin control trunk circuits 246, tone circuits 243, operator cut-through circuits 224, service circuits 244, coin tone receivers 250, and the announcement apparatus 252. The digit receivers, the outpulsers, the service circuits, the tone circuits, and the coin control trunk circuit, the coin tone receiver, and the announcement apparatus perform the same functions already described in connection with FIG. 1. The operator cut-through circuits are rudimentary trunk circuits whose function is to interconnect the talking circuits of each operator position with an appearance on the position link. The operator positions are shown on the right side of FIG. 2C and are designated 208-2 through 209-63. Each position circuit is individually associated with one of the position buffer circuits 208-2 through 208-63. Each operator position is also individually connected to one of the operator cut-through circuits 224-2 through 224-63, each of which on its left side extends to an individual position link appearance. The details of the equipment provided in each operator position, together with the manner in which each functions during the serving of the various types of calls that may be extended to a position is described in detail in the Jaeger-Joel specification, to which reference is made for an understanding of these details.

System control 105 on FIG. 1 is not shown as such on FIGS. 2 since it represents many circuits which are individually shown on FIGS. 2 and which together cooperate to control the operation of the system. These circuits on FIGS. 2 include stored program control 230, hereinafter referred to as "SPC," communications bus translator (CBT) 231, central pulse distributor (CPD) 232, signal distributor 233, trunk scanners 234, master

scanners 236, group gate 235, and position signal distributor 240. The embodiment of the invention shown on FIGS. 2, as well as on other drawing figures, comprises an electronic stored program controlled system which utilizes many circuits similar to those shown in detail in the copending application to A. H. Doblmaier et al., Ser. No. 334,875, filed Dec. 31, 1963. Doblmaier et al. discloses an electronic type local office which is controlled in its operation by a real time stored program processor. The Doblmaier et al. system is also disclosed in detail in the entirety of the September 1964 issue of the Bell System Technical Journal. Although the invention does not comprise a switching center in the sense that a call-routing operation is performed, it makes extensive use of circuits of the type shown in Doblmaier et al.

The SPC may be considered to be the "brain" or basic controlling mechanism for the entire TSPS center. It comprises a stored program real time machine having a processor 230A and a memory 230B. The processor performs arithmetical and logical operations on the data it receives from the memory, as well as on the data it receives from circuits external to the SPC, such as for example, from the scanners. The memory comprises bulk memory, which is supplied in sufficient quantity to store all the temporary and semipermanent information and data required for the operation of the TSPS center. As described in Doblmaier et al., as well as in Jaeger-Joel, the SPC, in performing its functions, receives signals from memory and from the scanners, performs the necessary arithmetical and logical operations in response to the received signals, and generates output commands which are transmitted to other circuits to control them in the performance of their required call functions. The circuits which respond to the SPC output commands are referred to as "peripheral circuits" since they are peripheral, or external, to the SPC.

The SPC communicates with the peripheral circuits by means of communication paths referred to in this specification as "buses." On FIG. 2, the buses which transmit the SPC commands to the various peripheral circuits are the 1-out-of-N address bus 239 and the binary address bus 238. The SPC transmits its output commands in binary form directly to the CBT over conductor paths 247 and 248. The CBT applies the SPC binary information to the binary address bus system. The CBT also translates the SPC binary output into a plurality of 1-out-of-N information bits and applies these to the 1-out-of-N address bus system. Thus, for each binary command received, the CBT applies a corresponding binary command to the binary address bus and, in turn, to the peripheral circuits served by this bus. Simultaneously, a 1-out-of-N type command is applied to the 1-out-of-N address bus and to the peripheral circuits it serves.

Each command transmitted from the SPC via the CBT to the address bus system functionally represents or indicates a task that is to be performed by a peripheral circuit. Each address bus system comprises a plurality of wires, most of which are connected to a plurality of peripheral circuits in common. Thus, a command applied by the CBT to a combination of address bus conductors is transmitted to all peripheral circuits to which this combination of conductors is connected. In the normal course of events, only one peripheral circuit responds to a command, even though many peripheral circuits receive it.

The input portion of each peripheral circuit is arranged so that it does not respond to an address bus command unless it has first been primed or unlocked by the reception of a special signal hereinafter termed an "enable pulse." The central pulse distributor operating under control of the SPC is the circuit which transmits enable pulses to the peripheral circuits. These pulses are transmitted over dedicated conductor pairs unique to each peripheral circuit. The SPC effects the operation of a selected peripheral circuit by causing the CBT to gate

onto the address bus system the command specifying the desired operation of the selected peripheral circuit and, at the same time, by causing the CPD to transmit an enable pulse over a dedicated conductor pair to the selected peripheral circuit. The peripheral circuits that operate in this manner include the switching network 204, signal distributors 233, trunk scanners 234, master scanners 236, group gate 235, the AMA recording facilities 237, and the teletypewriter facilities 238. The CPD and the CBT also operate in this manner. However, both their input commands and enable pulses are transmitted to them directly from the SPC.

The function of the trunk scanner is to monitor the current state of each trunk circuit and, upon command, report its findings to the SPC. The trunk scanner is connected to a plurality of circuit points within each trunk circuit, and each such circuit point it, in turn, individually connected to a different sensing device, termed a "ferrod" in the scanner. Each ferrod has a plurality of windings, one of which is connected across its associated trunk circuit point so that the magnetic state of the ferrod is controlled by the current applied to its winding by the trunk circuit point to which it is connected. The other windings of each ferrod are wired so that the scanner may be selectively controlled by the SPC to provide an indication of the existing circuit state. The master scanners are similar to the trunk circuit scanners except that they monitor the operational states of circuits other than trunk circuits. These include the service circuits, the digit receivers, and the coin tone receivers connected to the right side of the position link.

Ferrods are further described, *inter alia*, in the Baldwin-May Patent 3,175,042 of Mar. 23, 1965 and in an article entitled "No. 1 ESS Scanner, Signal Distributor, and Central Pulse Distributor," by Freimanis, Guercio, and May in the Bell System Technical Journal, vol. 43, page 2255 (September 1964, Part II). Ferrods are further described in the Jaeger-Joel specification.

The scanner ferrods are arranged into rows of 16 ferrods each. Each command received by a scanner specifies a ferrod row that is to be interrogated. The information resulting from the interrogation is transmitted to the SPC over bus system 240, designated "scanner answer bus." With this arrangement, the transmission of a command to a scanner instructing it to interrogate a particular row of ferrods, causes information to be transmitted back to the SPC signifying the current state of all circuit points within the system to which the plurality of ferrods in the interrogated row are connected.

The signal distributor 233 basically comprises a matrix or relay tree type translator, whose function is to receive the microsecond type signals from the CPD and the 1/N address bus and, in turn, transform them into signals having the persistence required to operate and release magnetic latching relays and the circuits of my system which utilize relays. These relays are primarily contained in the trunk circuits and in the service circuits. Signal distributors are further described in the aforementioned issue of the Bell System Technical Journal, as well as in the Jaeger-Joel specification.

The trunk link and position link circuits of the switching network 204 operate in response to the reception of the coincidently received signals from the CPD and the 1/N address bus system. These commands cause them to establish link connections between their left side and right side appearances. The paths by which these connections are to be established are not determined by the links but, instead, by the SPC in response to the information it receives from its memory. Switching networks of the type suitable for use with the present invention are disclosed in detail in the aforementioned issue of the Bell System Technical Journal, as well as in the patents cited in the Jaeger-Joel specification.

The AMA circuit 237 is connected to the binary address bus and it includes tape recorders together with

buffer registers and recorder control circuits. Its function is to record call charge data in response to SPC binary address bus commands. The main function of the Teletypewriter equipment TTY, and numbered 238, is to transmit printed instructions to maintenance men and the like under control of binary address bus commands.

The function of group gate 235 is to control the operation of the position signal distributor 240, in response to the commands it receives from the binary address bus. These commands represent lamp information that is to be transmitted to a particular operator position to assist the operator in serving a call currently at her position. The position signal distributor is similar to the signal distributor 233 in that it comprises a relay tree translator which receives the group gate output signals and translates them into signals having the persistence required to operate or release magnetic latching relays in the position buffer circuits 208-. Each position buffer circuit contains the relays required to control the lamp displays at its associated operator position.

Position scanner 242 transmits keyed information from the positions via the master scanner to the SPC regarding the state of each call currently connected to an operator position. Each position circuit contains a plurality of keys which may be depressed by an operator to generate call information. This information may comprise numerical data, such as calling and called numbers; it may comprise call charge data signifying the type of service requested by the calling party; and it may also comprise call status information, such as for example, signals requesting the disconnection of the operator position from the call. Position scanner 242 is connected to each key in each position and, by virtue of these interconnections, it continually monitors the state of each key; in response to the depression of any key at any position, it transmits signals back to the SPC, via the master scanner, signifying the key that is depressed as well as the position in which the key is located. The position scanner is shown in detail in the Jaeger-Joel specification, as well as in the G. Riddell application, Ser. No. 537,224, filed Mar. 24, 1966.

The following describes, with reference to FIG. 2, the manner in which the system of my invention serves a typical customer-dialed station-to-station call originating at a coin pay station. Under present practices, a call of this type arrives at the TSPS center after the calling party inserts the customary monetary amount required to obtain dial tone, and then dials the prefix required to signify station-to-station service followed by the 3-digit area code, if any, followed by the directory number of the called station. At the present time, it is contemplated that a prefix 1 will be dialed for station-to-station service, and therefore, assuming the call is directed to another numbering plan area, the calling party dials a prefix digit of 1, a 3-digit area code, plus the 7-digit directory number of the called station.

The originating office responds to the subscriber's dialing and completes a path therethrough to one of its outgoing trunk circuits, such as for example, 220A extending to the TSPS center. The seizure of this trunk circuit transmits a signal to the TSPS trunk circuit 203 to which it is permanently connected. The receipt of this signal changes the state of the trunk scanner ferrod which monitors the incoming side of the TSPS trunk circuit. The SPC is programmed so that both the trunk scanner and the master scanner scan all the circuits to which they are connected at a sufficiently high rate so that no newly received information is lost during the interval between scans. Thus, a short time after the trunk scanner ferrod for trunk 203 changes state, the ferrod row in which it is located is scanned and the resulting information transmitted back over the scanner answer bus 240 to the SPC. The SPC, by means of its memory, identifies the trunk circuit associated with the ferrod that has just changed state, analyzes the previous condition of this ferrod on

the preceding scan to determine whether this is a new change of state, and determines whether the change of state signifies a newly arrived seizure signal.

Once the SPC determines that this is a new seizure signal, it utilizes its memory to determine certain call parameters, such as for example, the calling and toll offices to which this trunk circuit is connected, the nature of the outpulsing that may be received from the local office, the nature of the signals that must be transmitted forward to the toll office, etc. Information of this type is commonly known as "trunk class information." It is stored on a semipermanent basis within the SPS memory for each trunk so that the SPC may determine the service required on each call.

Since the call currently being described is assumed to have originated at a coin pay station, this information must obviously be made available to the SPC so that the services peculiar to coin calls will be provided at the TSPS center. Two methods are currently available for informing the SPC whether a call is of the coin or noncoin type. The method utilized depends primarily upon the volume of traffic of each type originated by the local office. Dedicated trunks and trunk groups may be utilized for each type if the volume of traffic warrants it. In other words, if local office 201A generates enough coin type traffic, outgoing trunk 220A, TSPS trunk circuit 203, and incoming toll trunk circuit 221 may be reserved to serve coin traffic exclusively. In this case, all coin traffic originating at local office 201 and requiring a routing through toll office 221 would be served by the TSPS trunk circuits reserved exclusively for use by coin calls.

On the other hand, originating office 201 may not generate enough originating coin traffic to justify the use of separate trunk groups for this purpose. In this case, the coin traffic is served over the same trunks as are the non-coin traffic. These trunks are called "combined trunks" and information indicating the type of call is transmitted to the TSPS center in connection with the MF outpulsing of the calling and called station information. Each MF outpulsing operation is initiated with the transmission of a KP pulse and is terminated with a START pulse. Either the KP or the START pulse may comprise different combinations of frequencies, with each combination representing either the KP or the START pulse itself, together with a unique bit of class information. In connection with the present call, for example, a KP pulse of one frequency combination could represent coin type traffic, while a KP pulse comprising a different combination of frequencies would signify noncoin type traffic. It is assumed in connection with the present call that the TSPS trunk circuit 203 is of the combined type and that information signifying the type of call, insofar as its coin-noncoin characteristics are concerned, is supplied in connection with the MF outpulsing operation.

The SPC utilizes the class information stored within its memory to determine the type of service required on the call. It transmits the necessary commands, via the CBT and the CPD, to the switching network, instructing it to interconnect the T and R conductor appearances of the calling trunk circuit on network 204 with those of a suitable digit receiver. It is assumed that the information from the local office is to be received in MF form. Thus, the SPC causes an MF receiver to be connected by the network to the trunk circuit. When the receiver is attached, the SPC transmits coincident signals via the CBT and the CPD to the signal distributor, instructing it to operate relays within the trunk circuit 203 and digit receiver 207, so that an acknowledgment signal is sent back to the local office in the form of a polarity reversal on the T and R conductors. By means of subsequent polarity reversals, the SPC causes the MF receiver to transmit signals which cause the local office to outpulse the called and calling office information.

The call information outpulsed from the originating

75

office is received by the TSPS trunk circuit 203 and extended over its T and R leads via the switching network to the MF receiver. This circuit receives the call information, one digit at a time, and in response thereto, changes the magnetic state of a unique combination of master scanner ferrods to identify each digit. The master scanner scans all of its ferrod rows, under SPC control, and in so doing transmits serially back to the SPC over the scanner answer bus information signifying each digit outpulsed from the local office. The SPC operates in response to the receipt of this information and, once outpulsing is terminated, transmits commands to the switching network, instructing it to disconnect the digit receiver. The information transmitted to the TSPS center in connection with the local office outpulsing operation included a specially encoded START or KP pulse which, in addition to performing its normal functions, also, by virtue of its special encoding, instructs the TSPS center that this is a coin type call.

15 The SPC utilizes the calling and called station information, together with other pertinent information, such as for example, whether day or night rates are applicable, etc., to derive the charge rate and, in turn, the initial period deposit required at this time on the call. When this information is derived, the SPC instructs the switching network to complete a connection between the T and R conductors of trunk circuit 203 on the left side of the network with the right side network appearance of the announcement equipment, such as for example, appearance 253-1. Following the completion of this connection, the SPC controls the operation of the announcement equipment so that the required message is now reproduced and transmitted to the calling party. At this time, for example, he hears the following message: "This is a recording. Please deposit 60 cents for three minutes." The message might also advantageously request the party to deposit his coins only after he hears a spurt of tone indicating the system is prepared to receive the coin deposit information.

20 30 35 40 45 50 55 60 65 Upon the termination of the announcement, the SPC causes the switching network to disconnect the T and R conductors of the trunk circuit 203 from the announcement equipment and to connect them to the right side network appearance of the coin tone receiver. The coin tone receiver supplies a momentary tone pulse to the calling connection to signify that the system is prepared to receive the coin tone deposit signals. The receiver then monitors the tones generated in the call station as each coin is deposited. As previously mentioned, the calling station may advantageously be equipped with a coin deposit mechanism of the type disclosed in the aforementioned Andregg et al. patents, which utilizes a totalizer to generate a spurt of 2200-cycle tone in response to the deposit of each coin, with the number of tone spurts generated in response to each deposit signifying the amount of the coin in multiples of 5 cents. The SPC counts the number of tone pulses received by the coin tone receiver and determines whether the amount deposited matches that requested.

60 If the requested amount does not match exactly with the amount deposited, the SPC disconnects the call from the coin tone receiver and connects it to an idle operator position via its operator cut-through circuit. From there on out, the call is served in the manner disclosed in the Jaeger-Joel specification.

Let it be assumed that the amount deposited at the calling station matches that requested. After the SPC determines that the correct amount was deposited, it transmits commands to the switching network, instructing it to disconnect the call from the coin tone receiver and to establish a connection between an idle outpulser 206 and the T1 and R1 conductor appearance of the calling TSPS trunk circuit on the left side of the link. These conductors are connected internally within the trunk

circuit to the outgoing end extending via the OT and OR conductors to the toll office. The SPC determines from its memory the nature and quantity of the data that is to be outputted to the toll office, and it now transmits commands, via the CPD and the signal distributor, to control the outputter so that the data is transmitted forward, digit by digit, via the switching network, the T1 and R1 conductors of the trunk circuit, the outgoing end of the trunk circuit, and the OT and OR conductors, to the incoming trunk circuit 221 at the toll office. The toll office responds to this information in the conventional manner and establishes the forward connection to the terminating office in the called station. The switching network breaks down the connection between the outputter and the TSPS trunk circuit following the termination of outputting.

The SPC monitors and times the call and retains within its memory the information it has received from the originating office as well as that it has derived. The trunk scanner assists the SPC by transmitting information to the SPC on every scanning cycle pertaining to the on-hook or off-hook condition of both the calling and called stations. It has been assumed that the initial period of the present call is of three minutes duration. Therefore, the SPC, in timing the call, determines when three minutes have elapsed and, at this time, utilizes the information stored within it to derive the time and charge for a single overtime period. It causes the switching network to connect the T and R conductors of trunk circuit 203 with the announcement equipment. Once connected, the SPC controls the operation of the announcement equipment so that the calling customer hears the following type of message: "The initial period portion of your call has expired. The call is now entering overtime, for which the charges are 25 cents for each additional minute. Please signal when through." The network disconnects the announcement apparatus at the end of the message and the call proceeds in a normal manner, with the SPC monitoring the call and timing its duration.

At the call termination, when either party flashes or disconnects, the SPC (1) determines the chargeable overtime duration applicable, (2) computes the charge to be collected for the overtime, and (3) connects the T and R conductors of the TSPS trunk circuit 203 to the announcement equipment which communicates its message to the calling station. Let it be assumed, for example, that the chargeable overtime for the call is four minutes, and for which the charge is one dollar. Therefore, the calling customer is requested by the announcement apparatus to deposit one dollar for four minutes of overtime. The SPC next commands the network to disconnect the call from the announcement apparatus and connect it to the coin tone receiver, which monitors the collection of the requested charges in the same manner as already described in connection with the collection of initial period charges. If the amount deposited exceeds, or is less than, that requested, the call is routed to an operator. If the amount deposited matches the amount requested, the trunk circuit 203 is disconnected from the coin tone receiver and is restored to a normal condition to prepare it for the serving of subsequent calls. The network connects the T and R conductors of trunk circuit 203 with the coin control trunk circuit 246, which functions in the manner described in the Jaeger-Joel specification to collect the coins deposited at the calling station.

As its last function in connection with the serving of this call, the SPC transmits the call information that it has accumulated to the AMA recording facilities, which record the data applicable to the call. This charge data may include the call type, the connect and disconnect times, together with the calling and called station numbers.

It was assumed, in connection with the preceding, that the charges were collected on a postpay overtime basis. As has been priorly mentioned, overtime charges are sometimes collected on a prepay basis at the beginning

of each overtime interval. If it is desired to serve the calls in this manner, the circuit operations would be similar to those already described, except that the call would be interrupted at the beginning of each overtime interval and, at that time, the SPC would (1) compute the time and charge for a single overtime period, (2) connect the T and R conductors of the TSPS trunk circuit to the announcement equipment, (3) cause the required message to be transmitted to the calling station, (4) disconnect the call via the network from the announcement equipment and connect it to the coin tone receiver, and (5) monitor the coin deposit tones received from the coin tone receiver to verify that the amount deposited matches that requested. If the deposit is of the correct amount, the coin tone receiver is disconnected from the call and the parties are left free to converse for the overtime interval duration. The sequence of actions just described occurs at the beginning of each subsequent overtime interval for the call's duration. At the call termination, the TSPS trunk circuit is restored to a normal condition since no further charges are due on the call. The SPC controls the recording of AMA data in the same manner as already described.

TSPS trunk circuits—FIGS. 4 and 5

25

The function of each TSPS trunk circuit, such as circuit 203 on FIG. 2A, is to extend a call from its local office appearance to its toll office appearance and, in so doing, temporarily bridge service circuits within the TSPS center onto the calling connection in order that certain call service may be more efficiently provided at the TSPS center than it may be at either the local or toll offices. Once this service is provided, the service circuits are disconnected and the calling and called stations remain connected for the call duration via the TSPS trunk circuit. The TSPS center monitors the call and restores the trunk circuit to its idle state upon the call termination.

30

FIG. 4 discloses the circuit details of a TSPS trunk circuit arranged for MF signaling from the local office. FIG. 5 pictorially illustrates all the states of this trunk circuit in accordance with the principles set forth in the article entitled "The Method for Synthesis of Combinational Logic Circuits," by M. Karnaugh in the American Institute of Electrical Engineers Transactions, line 72, pages 593 through 599, of November 1953. Each individual rectangle on FIG. 5 is designated to indicate the functional state of the trunk circuit at the time the relays are operated whose brackets encompass the rectangle. For example, the box numbered 7 and entitled "Coin Control and Ringback" indicates the state of the trunk circuit at the time that relays A, B, and C are operated.

35

The circuit of FIG. 4 is connected by means of its IT and IR conductors on its left side to the outgoing end of originating office 201A, shown on FIG. 2A. On its right side, the trunk circuit is connected via its OT and OR conductors to the toll office 202. Its T, R, T1, and R1 conductors in the conductor group 404 extend to the trunk side of link 204A on FIG. 2A. Conductors T and R extending to the link permit the position side circuits (the right side) of the link 204B to be connected to the incoming end of a calling connection. The T1 and R1 conductors permit the position side circuits to be connected to the outgoing end. Conductor group 405 connects the trunk scanner ferrods L and R to the appropriate points within the trunk circuit of FIG. 4 so that it may monitor the potential states of the incoming and outgoing loops. The conductor group 406 comprise the circuit paths by which the signal distributor may apply signals to the magnetic latching relays A, B, and C to selectively operate and release them.

40

The following paragraphs describe the detailed operation of this trunk circuit, together with a description of the circuit states it assumes during the serving of a coin

45

50

55

60

75

call involving overtime. This description is with reference to the numbered circuit states shown on FIG. 5.

The trunk is in an idle condition prior to its seizure by the originating office. This state is numbered 0 and is designated "idle" on FIG. 5. The trunk assumes state 4 when its originating side is seized as the originating office applies a seizure signal and attempts to extend a call forward to the toll office. This seizure signal comprises what is commonly known as a "dry loop" in the outgoing trunk circuit of the originating office. This "dry loop" places a D-C short across the IT and IR conductors. The seizure of the IT and IR conductors energizes ferrod L, which transmits a seizure signal to the SPC which, in turn, commands the signal distributor to operate relay C over conductor SD2. The operation of relay C operates its transfer contacts connected to terminals 423 and 424 to reverse the polarity of the supervisory potential applied by the L ferrod to the IT and IR conductors.

The SPC next commands the switching network to connect the T and R conductors of this trunk circuit with the corresponding conductors of a digit receiver of the MF type. The SPC commands the signal distributor to operate relay B to put the trunk circuit into its state 6 when the connection to the MF receiver is established. The operation of relay B operates its break contacts to the left of terminals 425 and 426 to disconnect the path by means of which the supervisory potentials are applied to the IT and IR conductors by the L ferrod. The MF receiver at this time applies the required supervisory potentials to these conductors back to the originating office, as described in detail in the Jaeger-Joel specification. The called and calling station information is subsequently outpulsed by the originating office to the MF receiver. When the outpulsing operation is terminated, the trunk reassumes its circuit state 4, in which relay B is released, leaving only relay C operated.

The SPC knows from the call information available to it that the call is from a coin pay station and is of the station-to-station type. Therefore, at this time, the SPC leaves the trunk circuit of FIG. 4 in state 4 and establishes a link connection between the T and R conductors of both this trunk circuit and the announcement equipment. Once the connection is completed, the required announcement is sent back to the calling station under control of call information derived by the SPC. As described in the preceding sections, the message at this time would specify the duration of the initial period together with the amount that is to be deposited in payment therefor.

Immediately upon the conclusion of the message, the SPC disconnects the trunk T and R conductors from the announcement apparatus and transfers them to an idle coin tone receiver of the type shown in FIG. 9. Simultaneously therewith, it reoperates the B relay of FIG. 4 to put the trunk back into its HOLD state 6 in which the supervisory potentials supplied by the L ferrod to the connection are removed. The potentials supplied to the T and R conductors by the coin tone receiver comprise the supervision for the call as long as the connection of the coin tone receiver remains in effect. The coin tone receiver, at this time, receives and passes to the SPC signals indicating the amount deposited at the calling station. The coin tone receiver is disconnected from the trunk circuit upon the conclusion of the coin deposit operation at the calling station. The trunk circuit is restored to state 4.

The SPC utilizes the information received from the coin tone receiver to determine whether the required amount was deposited. After satisfying itself that the correct charges were deposited, the SPC determines that the call may be completed and establishes a link connection between the trunk T1 and R1 conductors with an MF outpulser which outpulses to the toll office the information it requires. The A relay is operated to put the trunk in its cut-through state 5 following the disconnection of the outpulser.

The incoming and outgoing portions of the trunk are 75

now connected. The R ferrod is connected in series with the windings of inductance LA, and it monitors the potentials applied to the OT and OR conductors by the toll office incoming trunk circuit. The polarity of these conductors is reversed when the called party answers. This reversal is detected by the SPC and is utilized to indicate the time at which the charging for the call is to commence.

The trunk circuit remains in its cut-through state 5 until the termination of the initial period, at which time relay B is operated to put the trunk circuit into its coin control state 7. The SPC at this time connects the T and R conductors of the trunk circuit via the switching network to the coin control trunk circuit of FIGS. 6 and 7 which, as described in detail in connection with a portion of the specification pertaining thereto, applies the necessary potentials back to the originating office to collect the coins at the calling station. This operation takes only a second or less; and upon its conclusion, the coin-collect trunk circuit is disconnected and the trunk relay B on FIG. 4 is released to restore the MF trunk circuit to its cut-through state 5.

The SPC utilizes the information stored within it to derive overtime period charge information, and it now connects the trunk T and R conductors via the switching network to the announcement apparatus which, under SPC control, transmits a message to the calling party, advising him that the call is entering overtime and also advising him of the duration and charge for a single overtime period. The announcement apparatus is disconnected from the call upon the conclusion of the transmission of its message, and the trunk circuit remains in its cut-through state 5 until the completion of the call.

The call termination is detected by the R or L ferrod and the SPC when either party hangs up, or when the calling party flashes his switch hook. The SPC at that time releases trunk relay A to put the trunk circuit in its release forward state 4. This releases the forward connection. The trunk circuit remains in its state 4 and the SPC at this time computes the times and charges due on the call and connects the T and R conductors of the trunk circuit to the announcement apparatus which, under SPC control, transmits a message to the calling station indicating the derived time and charge information. The announcement apparatus is disconnected upon the conclusion of the message. The SPC next connects a coin tone receiver to the T and R conductors and the coin deposit information for the overtime portion of the call is received. The trunk is put into state 6 for this operation. The coin tone receiver is disconnected from the call upon the termination of the coin deposit operation and the trunk circuit is returned to state 4.

The SPC next connects the trunk T and R conductors to the coin-collect and ringback trunk circuit. The MF trunk circuit remains in its state 4 until the coin-collect trunk circuit is connected, and then, once the connection is established, the trunk circuit is advanced to its HOLD state 6 by the operation of its B relay. This removes the MF trunk circuit supervision and puts the supervision of the call under control of the coin-collect and ringback trunk circuit, in the manner priorly described. Following the coin-collect operation, the coin-collect and ringback trunk circuit is disconnected from the call and the MF trunk circuit is restored to its state 4 by releasing the B relay. Next, the SPC releases the C relay to restore the MF trunk circuit to its idle state 0 in preparation for the serving of the subsequent call.

Coin-control trunk circuit—FIGS. 6-8

The purpose of the coin-control trunk circuit shown as element 246 on FIG. 2A is to transmit back to an originating office the signals it requires on coin calls to perform coin-collect, coin-return, and ringback functions. The ringback signal is also used on noncoin calls. The control signals generated by this circuit may be either of the AC or

DC type, depending upon the requirements of the originating office. For AC signaling, a unique combination of frequencies representing the function to be performed is generated and transmitted back to the originating office. A unique combination of DC potentials is applied for each DC control signal.

The coin-control trunk circuit is connected to a call by the switching network under control of the SPC. The SPC determines when the connection is to be made, either automatically or in response to the reception of a signal from the operator position currently connected to the call. Thus, a coin-collect, coin-return, or ringback function may be initiated automatically by the SPC, or alternatively, it may be initiated by the SPC in response to a signal to this effect from an operator position. Once the coin-control trunk circuit is connected to a call, the circuit operations within it which are necessary for the generation of the required control signals are controlled by the signal distributor operating under control of the SPC. Various circuit points within the coin control trunk are connected to master scanner ferrods in order that information regarding its circuit state may be available to the SPC.

The details of a coin-control trunk circuit are shown on FIGS. 6 and 7 when arranged as shown in FIG. 8. The T and R conductors on the upper left portion of FIG. 6 extend to the position link, which operates under control of the SPC during the serving of a call to extend these conductors through to those of a calling trunk circuit, such as MF trunk circuit 203. Frequency generator 603 generates three signals of different frequencies, and the AC control signals required on a call are obtained by selectively connecting two of the three frequency sources to the T and R conductors. The plus 130-volt potential at terminal 604, the negative 48-volt potential at terminal 605, and the ground potential at terminal 607 comprise the potential sources utilized when DC signals are required by an originating office. Relays A, B, C, and D on FIG. 7 are of the magnetic latching type, and they operate and release in response to signals from the signal distributor. Relays A, B, and C may also be released by means of locally generated signals originating at the plus 24-volt potential on terminal 704. Relays T, CT, T1, RB1, and RB2 operate and release by means of circuit paths internal to the trunk.

When the coin-control trunk circuit is initially connected by the switching network to a call, none of its relays are operated and no potentials are applied over the T and R conductors to the calling circuit. Thus, for a brief time, the TSPS trunk circuit remains in control of the connection. The coin trunk remains in this condition until one of relays A, B, C, or D is operated. Relay A is operated to initiate a coin-collect operation; relay B is operated to initiate a coin-return operation, while relay C is operated to initiate a ringback operation. Relay D is operated for a DC signaling operation together with one of relays A, B, or C. Relay D is not operated for an AC signaling operation.

Let it first be assumed that the circuit is to perform a coin-collect operation by AC signaling. This requires the operation of relay A. Relay A is operated by the signal distributor subsequent to the connection of the coin trunk to the calling trunk circuit. The signal distributor operates relay A by applying a negative pulse to conductor SD00 and a ground pulse to conductor SDG. The operation of relay A closes its make contacts on FIG. 6 to connect the windings of ferrod F0 in the master scanner to the T and R conductors. This circuit path includes break contacts of relay D connected to terminals 601 and 602, make contacts of relay A, two windings of the L inductance, the windings of ferrod F0 to ground on its left winding, and to negative battery on its right winding. This path applies negative 48 volts to the T conductor and ground to the R conductor. The SPC now removes the TSPS trunk circuit supervision, and the potentials

applied by the coin control trunk circuit constitute the supervision of the call for the time being.

Relay A, operated, operates relay CT from the terminal 701 ground in series with the break contacts of relay T. Relay CT, operated, operates relay T, which in turn opens the path for relay CT, which now begins a slow-release operation that occupies roughly 200 milliseconds. Relay T, in operating, also extends the terminal 606 ground through the break contacts of relay T1 to energize ferrod F1.

When relay CT releases, its break contacts extend the terminal 606 ground to operate relay RB2. Relay RB2, in operating, closes its make contacts on FIG. 6 to complete the connection between the T and R conductors and the frequency generator 603. At this time, the following circuit is closed to connect the 1100-cycle frequency to the T conductor; terminal 601, break contacts of relay D, make contacts of relay A, terminal 622 make contacts of relay RB2, capacitor C1, break contacts of relay C, make contacts of relay A, to the 1100-cycle generator. The following circuit is also closed at this time to apply a 700-cycle signal to the R conductor: terminal 602, break contacts of relay D, make contacts of relay A, terminal 623, make contacts of relay RB2, capacitor C2, break contacts of relay B, make contacts of relay A, to the 700-cycle generator.

The application of 700 cycles and 1100 cycles to the T and R conductors at this time effects a coin-collect operation in the originating office. The energization of ferrod F1 when relay T operates constitutes a signal to the SPC that the coin-collect signal transmits back to the originating office after a delay of 200 milliseconds, as required for the release of relay CT and the subsequent operation of relay RB2. The operation of relay T extends the terminal 708 negative battery through make contacts of relay T to the terminal 709 input of the timer 711. The timer operates in response to the reception of this negative potential and, after a delay of one second, operates relay T1, whose break contacts open the circuit for ferrod F1. The de-energization of this ferrod constitutes a signal to the SPC that the coin-collect signal has been transmitted.

This completes the function of the coin-control trunk on this call, and the SPC, once it receives the signal that ferrod F1 has been de-energized, commands the signal distributor to release relay A by applying a positive pulse to conductor SD00 in a ground pulse to conductor SDG. At the same time, the SPC commands the switching network to break down the connection between the calling TSPS trunk circuit and the coin-control trunk circuit. The release of relay A restores this circuit to normal.

The preceding has described the operation of the coin-control trunk circuit, and in particular, the manner in which it generates a coin-collect signal by means of AC signaling. It functions in a similar manner to generate coin-return signals when relay B is operated and to generate a ringback signal when relay C is operated. These signals are generated in a manner identical to that already described for a coin-collect operation in connection with the operation of relay A. The only difference is that a coin-return signal requires the operation of relay B and applies 1100 cycles to the T conductor and 1700 cycles to the R conductor. Similarly, a ringback function with relay C operated applies 1700 cycles to the T conductor and 700 cycles to the R conductor.

The following describes the manner in which this circuit operates to send back DC control signals to the originating office. As in the case for AC signaling, no relays are operated at the time the coin-control trunk is connected to a call and thus the supervision of the call remains momentarily under control of the calling TSPS trunk circuit. Subsequently, the signal distributor operates relay D whenever DC signaling is to be used and then time operates one of relays A, B, or C, de-

pending upon the specific control signal that is to be supplied. Let it be assumed in this case that relay B is operated for a coin-return function. The operation of relay D operates its transfer contacts connected to terminals 601 and 602 so that a path is closed to interconnect the T and R conductors with the potentials as supplied by the windings of ferrod F0. This path includes make contacts of relay D, break contacts of relay CT, windings of the L inductance, and windings of ferrod F0. Negative battery is applied to the T conductor and ground to the R conductor at this time in the same manner as already described for AC signaling.

The operation of relay B for a coin-return function operates relay CT from the terminal 701 ground. The operated condition of relays D and CT closes a path through their make contacts to energize the F1 ferrod with the terminal 606 ground. The energization of this ferrod constitutes a signal to the SPC that the coin-return signal is about to be generated and applied back to the originating office. The operated state of relays D and CT also closes another path through their make contacts to apply a negative battery to terminal 709 of the timer 711. This timer operates in response to this signal and, after a delay of one second, operates relay T1. The DC signaling potentials are applied to the T and R conductors during the interval whose beginning is signified by the operation of relay CT and whose termination is signified by the operation of relay T1 which, in operating, closes a path over its make contacts to apply plus 24 volts from terminal 704 to the winding of relay B to release it. During this interval, the potentials applied to the T and R conductors are plus 130 volts on the R conductor and negative 48 volts on the T conductor. The path for the R conductor is as follows: terminal 602, make contacts of relay D, make contacts of relay CT, break contacts of relay C, make contacts of relay B, break contacts of relay A, resistor R7, to the plus 130 volts on terminal 604. The circuit for the T conductor is as follows: terminal 601, make contacts of relays D and CT in series, terminal 612, break contacts of relay C, make contacts of relay B, break contacts of relay A, terminal 618, resistor R6A, to the negative 48 volts on terminal 605. This combination of potentials is transmitted back to the originating office, which performs a coin-return function in response thereto.

As already mentioned, the operation of relay T1 releases relay B, which in turn removes the DC control potentials from the T and R conductors. The release of relay B also releases relay CT, and the reclosure of their break contacts connect the potentials on the windings of ferrod F0 to the T and R conductors. The release of relay CT also opens its make contacts to de-energize ferrod F1 as a signal to the SPC that the coin-return signal has been generated and transmitted to the originating office. The SPC then restores the circuit to normal by commanding the signal distributor to release relay D.

The following describes the manner in which this circuit operates to generate a DC ringback signal. The circuit is in its idle condition when initially connected to the call in the same manner as priorly described. Relay D is operated to connect the windings of ferrod F0 to the T and R conductors to permit this circuit to assume supervision of the connection. This applies negative 48 volts to the T conductor and ground to the R conductor. Subsequently, relays D and C are operated to generate the ringback signal. The operation of relay C operates relay CT by means of its make contacts from the terminal 701 ground. At this time, neither relay A nor B is operated, and therefore the terminal 705 ground is not applied to input terminal 710 of the timer. This causes its timing interval to be increased from one to two seconds. Make contacts of relays D and CT, in series, at this time connect the terminal 708 negative battery to input terminal 709 of the

timer to cause it to begin a two-second timing operation, at the end of which it operates relay T1. The operated state of relays D and C closes a path through the make contacts of both to apply the terminal 703 ground through the break contacts of relay RB2 to the winding of relay RB1 to operate it. The operation of this relay closes a path to extend the ground on terminal 712 through its own make contacts to the winding of relay RB2 to operate it. This relay, in operating, opens the path of relay RB1, which then releases and in turn releases RB2. This alternate operation and release of relays RB1 and RB2 continue for the duration of the interval timed by the timer 711. At the end of the timing interval, relay T1 operates and, by means of its make contacts, applies a positive 24-volt potential to the left winding terminal of relay C to release it. The release of relay C releases relay CT and opens the path of relay RB1 to stop the alternate operation and release of relays RB1 and RB2.

During the two-second timing interval during which the ringback potentials are applied to the T and R conductors, the condition of the circuit is such that the R conductor may be extended through make contacts of relays D, CT, and C in series, to the terminal 614, while the T conductor may be extended through make contacts of relays D, CT, and C, in series, to the terminal 617. Terminal 614, and in turn the R conductor, is connected to the terminal 607 ground whenever one or more of relays RB1 and RB2 are released, and alternately is connected through resistors R6 and R6A to the negative 48-volt potential on terminal 605 whenever both of relays RB1 and RB2 are operated. Similarly, the terminal 617 and, in turn, the T conductor, are alternately connected between the terminal 607 ground (when both relays RB1 and RB2 are operated) and the negative 48-volt potential on terminal 605 (whenever one or more of these two relays are released). The transmission of these flashing reversals of polarities back to the originating office for the two-second period causes it to perform a ringback function of the calling line. The ringback signal is terminated when relay T1 operates to release relay C and, in turn, relay CT. The release of relay CT reconnects the windings of ferrod F0 to the T and R conductors as a supervisory potential.

Ferrod F1 is energized when relays D and CT are operated, as a signal to the SPC that the circuit is about to generate its required control signal. Subsequently, the release of relay CT, in response to the release of relay C, de-energizes the ferrod as a signal to the SPC that the circuit has performed its intended function. The SPC then commands the signal distributor to release relay D and restore the circuit to its idle state. At this time, the SPC simultaneously commands the switching network to disconnect the coin-control trunk from the call.

Coin tone receiver—FIG. 9

The function of the coin tone receiver, shown as element 246 on FIG. 2A, is to receive and detect coin deposit tone signals generated at a calling coin station. These signals are transmitted from the calling station, through the originating office, over the IT and IR conductors, to the TSPS center, through the TSPS trunk circuit to its T and R conductors, and through the switching network to the T and R conductors of the coin tone receiver shown on FIG. 9. The tone signals received by this circuit are filtered, detected, and an indication thereof passed to the SPC by means of master scanner ferrods.

The T and R conductors of this circuit are connected to the outer ends of windings 902 and 903 of transformer T1. The inner ends of these two windings are connected over conductors 911 and 912 to battery and ground supplied by the two windings of the F0 ferrod. These potentials on the T and R conductors permit the coin tone receiver to maintain supervision of the call when it is connected to the T and R conductors of the TSPS trunk circuit. Ferrod F0 permits the SPC to monitor the T and R path back to

the originating office and, in turn, to supervise the connection.

A momentary tone signal is applied to a call immediately upon its connection to a coin tone receiver to inform the calling party that he may proceed to deposit the coins representing the charges specified by the announcement apparatus. This tone signal is supplied by the oscillator 915, which is connected to the T and R conductors in series with make contacts of relay 9-A and capacitors C1 and C2. The SPC and the signal distributor together effect this momentary connection of oscillator 915 by transmitting the necessary signals to conductor SD90 to operate relay A and then release it in a short time, such as for example, in 500 milliseconds after it is operated.

The coin tone signals received in response to the coin deposits are induced in windings 902 and 903 of transformer T1, transferred to winding 904, and applied via capacitors C7 and C8 to the filter and frequency detector 905. This element comprises the necessary filters and detection apparatus to enable it to apply output signals to terminals 910 and 920 only in response to the reception of a coin tone signal of the proper frequency. This output signal is applied over conductor 916 to ferrod F1 to change its magnetic state, as an indication to the SPC that a coin tone pulse is being received. The output signal on terminal 910 is applied via conductor 909 to the input of the pulse width validity check circuit 908. This circuit times the persistence of each coin tone pulse and, if it is of the proper duration, generates an output signal which is applied over conductor 917 to the 20-millisecond delay circuit 907. Circuit 908 is provided to prevent the coin tone receiver from responding to noise impulses and other transients which do not represent valid signals.

The output of circuit 907 is connected to the FC ferrod. In order to prevent the voice simulation of coin tone pulses, the response of the FC ferrod to the reception of a valid coin tone pulse is delayed for 20 milliseconds. Once the FC ferrod is switched, it is held in that state for 20 milliseconds after the coin tone pulse has ceased. This is done to prevent the FC ferrod from following any noise pulses which might affect the frequency detector output and cause the SPC to recognize the continuation of a current pulse as the start of a new pulse. The SPC does not scan ferrods F1 until it first detects that the FC ferrod is switched, which switching occurs 20 milliseconds following the reception of a valid coin tone pulse. Once the SPC determines that the FC ferrod is switched, it then scans the F1 ferrod to determine the presence of a valid coin tone pulse. The F1 ferrod is not scanned again by the SPC until it detects that the FC ferrod is restored to its normal condition (20 milliseconds after the coin tone pulses cease), and then, in response to the reception of the next coin tone pulse, has once again reverted to the magnetic state it assumes during the reception of a valid coin tone pulse.

The SPC monitors ferrods FC and F1 to determine the number of coin tone pulses received by the circuit of FIG. 9 following its connection to a call. This information, in turn, is utilized to determine whether the amount deposited at the calling station matches that requested in the recorded announcement. The SPC disconnects this circuit from the call and restores call supervision, to trunk circuit 203, for example, upon the conclusion of the coin tone signaling operation at the calling station.

Stored program controller (SPC)—FIGS. 10, 11, 12A-12D, 13

The SPC, shown as element 230 on FIG. 2B, comprises a stored program machine having a processor 230A and a memory 230B. The memory stores both programmed instructions and data. All instructions, and some data, are stored on a relatively permanent basis and are changed only infrequently from time to time. Other of the data is relatively temporary in nature, and it may be

entered into memory, modified, and erased during the serving of a call. The programmed instructions form the entirety of the vocabulary of the computer, and they provide the intelligence necessary to instruct the processor in the many functions required of it under any of the many call situations the SPC may encounter. The processor monitors and controls peripheral equipment by performing logical and/or arithmetic operations on data temporarily stored in registers within it, under control of the programmed instructions, and by transmitting to the peripheral equipment output information or commands generated while performing these operations. Although the processor may perform many different functions, it is capable of executing only one instruction at a time under control of the programmed memory.

The SPC, in performing its functions, either directly or indirectly, controls the operation of every circuit in the system. All commands specifying an operation in another circuit originate within the SPC and all answers signifying the existing operational state of many circuit points within the system are returned to the SPC. Certain instructions result in actions which are entirely confined within the SPC. For example, an instruction or series of instructions may command the SPC to perform logical and/or arithmetic operations on the data currently contained within it. Other instructions may cause the SPC to command a peripheral circuit to perform an operation which results in an answer being transmitted back to the SPC via the scanner. An instruction, for example, may result in a command being sent to the scanner to read or interrogate a specific row of ferrods. The results of the interrogation is transmitted over the scanner answer bus back to the SPC, where the information is stored temporarily either in memory or in index registers within the processor until it can be later utilized.

The SPC communicates primarily with the CBT's (communication bus translators), the CPD's (central pulse distributors), and the scanners. The output signals of the SPC are commonly referred to as "commands" since they cause the circuit receiving them to perform the operation specified by the command. The commands transmitted to the CBT's are applied over circuit paths 247 and 248 and they instruct the CBT's to apply their own output commands to the address buses which, in turn, transmit them to the peripheral circuits to which they are connected. The SPC output commands are received by the CPD's over circuit paths 210 and 212 and they instruct the CPD's to unlock the receiving portion of a specified peripheral circuit in order that it, and only it, may receive and register the command currently on the address bus to which the specified peripheral circuit is connected.

The scanner answer signals are transmitted over the scanner answer bus 240 back to the SPC. The information represented by these signals signifies the current state of many circuit points within the system. Each such circuit point is associated with an individual ferrod in the scanner and the plurality of ferrods within a scanner are divided into rows. When the SPC desires to obtain information regarding the state of a specified circuit point, it causes commands to be transmitted to the scanner, which instructs it to scan the ferrod row containing the ferrod individual to the specified circuit point. The scanner answer transmitted to the SPC as the result of this interrogation represents the existing state of the specified circuit point as well as all of the other circuit points individual to the remainder of the ferrods in the interrogated ferrod row.

FIG. 10 discloses in greater detail the relationship between an SPC 1000 and the circuits with which it communicates. The SPC comprises processor 1008 and memory 1007. The processor retrieves either data or instructions from memory by a read operation and it enters information into memory by means of a write operation. The input bus for memory 1007 is element 1001; the

output bus is element 1002. FIG. 10 also discloses CBT 1019, CPD 1020, and a plurality of scanners which are represented generally as element 1021. The processor transmits commands to the CBT over bus 1010 and to the CPD over 1011. It receives information from the scanners over bus 1025 and from the CBT and CPD over bus 1026.

Additional details of the SPC are shown on FIG. 11. This figure discloses a processor 1101, a memory 1102, the circuit paths interconnecting these two elements, as well as the circuit paths interconnecting the processor with circuits external to the SPC.

Memory 1102 is functionally subdivided into a plurality of portions designated A, B . . . n, each of which stores the program and data required to enable the SPC to perform the many separate functions required for the operation of the system. The Memory Read and Write Control Circuit 1105 within the processor controls the operations required to read data and instructions out of and enter data into memory. The information to be written into memory is applied to it over bus 1104 from the output of circuit 1105. Similarly, the information that is read from memory is applied by means of bus 1103 to circuit 1105. Each portion of memory is represented by an address, as is typical in stored program machines, and therefore in performing each read and write function, circuit 1105 obtains the address of the pertinent portion of memory from address generator 1107 over path 1106. The memory access register MAR, shown as element 1110, transmits to circuit 1105 the information that is to be entered into memory on write operations, and on read operations it receives from circuit 1105 the information extracted from memory. The information the MAR receives from memory on a read operation is transmitted to other elements (not shown) within the processor over path 1111. Similarly, the MAR receives from these other elements the data that is to be entered into memory on a write operation over path 1112.

Since the details of the processor comprise no part of the invention, many of the elements with which the MAR communicates are shown only functionally. However, included in the processor is the circuitry required to operate upon and manipulate the data stored within it so that both logical and arithmetic operations may be performed. This circuit is represented generally by the box entitled Arithmetic and Logic Circuit and shown as element 1117.

The index registers 1114 cooperate with circuit 1117 to perform arithmetic and logical operations upon the data received by the processor both from memory and from circuits external to the SPC. The index registers are also used to receive and register temporarily the scanner answer information. This information is received over path 1118 and, once received, it is stored within the index registers until it may be acted upon and then either entered into memory, utilized for other purposes, or discarded. Checking circuit 1116 receives the various check signals, parity signals, all-seems-well signals, and WRMI signals which must be received by the SPC in response to the various commands it transmits to other circuits before it proceeds with another command. The output commands generated by the SPC are applied to external circuits by the circuit entitled "SPC output steering and control circuit" and designated as element 1120. Cable 1121 transmits commands from the SPC to the CBT; cable 1122 transmits commands from the SPC to the CPD; and cable 1123 transmits WRMI pulses to the circuits requiring them.

The SPC is shown primarily in diagrammatic form on the present drawing figures, including FIGS. 2B, 10, 11, and 12, since its detail comprise no portion of the present invention and since stored program controllers suitable for use in my invention are disclosed elsewhere. For example, the aforementioned Doblmaier et al. application discloses in complete detail a stored program controller which may be utilized to generate the control signals required to operate the circuits of my invention. The

Doblmaier et al. stored program controller is further described in complete detail in the aforementioned Bell System Technical Journal of September 1964, which issue is devoted in its entirety to an electronic switching system and with approximately 50 percent or more of this issue being devoted to details of the stored program controller. Also, if desired, a stored program controller whose processor is shown in Kettley et al. application, Ser. No. 422,313, filed Dec. 30, 1964, may be utilized instead of the one shown in detail in Doblmaier et al. Since the details of stored program controllers suitable for use to generate the signals required by my system are shown in detail in the prior art, the disclosure of the present specification has been simplified by disclosing only those details of an SPC as are required for an understanding of my invention.

On FIG. 11, the SPC memory 1102 is divided into a plurality of elements designated A, B . . . through n, each of which stores the data or information pertaining to a different operation the SPC may perform. Each memory element is connected by a separate path to a write bus 1104 positioned atop the memory and to a read bus 1103 positioned underneath the memory. The processor effects a write operation by simultaneously gating onto the write bus the address of the portion of memory that is to be written into, together with the information that is to be written. Similarly, the processor effects a read operation by gating onto the read bus a read command together with the address of the portion of memory that is to be read.

FIGS. 12A through 12D, when arranged as shown on FIG. 13, disclose additional details regarding the manner in which the memory may be subdivided by its call-servicing functions. The memory elements are arranged into a plurality of rows on FIGS. 12. Write bus 1104 and read bus 1103 extend vertically on the right side of these figures. A branch of the write bus extends horizontally atop each memory row, and each such branch is connected by the indicated arrowed paths to each section of memory in its row. Similarly, a branch of the read bus extends horizontally beneath each row, and each branch is connected by the indicated arrowed paths to each memory section in its row. These interconnections permit the processor to read and write into any portion of memory in the same manner as described in connection with FIG. 11. The connections to the processor are shown in the upper right-hand corner of FIG. 12A.

The top row represents the memory elements associated with the TSPS trunk circuits and their control. Element A is entitled "trunk class information" and stores the many parameters pertaining to each trunk circuit, including the class of calls served thereby. Element B is entitled "status" and registers information signifying the status, i.e., busy or idle, of each trunk circuit. Element C comprises the trunk monitor program and governs the operation of the SPC in controlling the trunk circuits. The service request program D enables the SPC to determine the initiation and termination of service requests by the trunk. Memory E stores a mark indicating whether or not operator assistance is required on calls served by each trunk circuit. Element F comprises the calling number register for each trunk circuit while element G comprises the called number registers. Memory element H stores class-of-charge information. Element J stores the answer time and element K stores the disconnect time for each trunk circuit. Element L stores the credit card number for credit card calls. Element M stores the operator work time. The operator work time is subtracted from the total time of the call in order to derive the true chargeable time. Element N stores a number indicating the network appearance of each trunk circuit on the switching network.

Element P is the first of the elements pertaining to the coin control trunk circuits and stores information

representing the status of each such circuit. Element Q comprises the control program associated with coin refund operations. Element R comprises the control program associated with coin-collect operations, while element S comprises the control program for re-ring operations. Element T comprises the remaining monitor program required for the operation of the coin control trunk circuit. Element U stores information signifying the appearance of each such circuit on the switching network.

Element V is the first portion of the memory pertaining to the switching network and it stores the network map. Element W stores path memory information, i.e., information pertaining to established connections in the network. Element X stores the overall control program for the network. Element Y comprises the program required to control the operation of the AMA equipment, while element Z comprises the program required to control the operation of the outpulsers.

Element AA stores status information for the digit receivers, element AB comprises the control program of the digit receivers, element AC comprises a program which translates the digits received into binary form suitable for storing in memory, and element AD stores information signifying the network appearance of each digit receiver.

Element AE comprises the programs required to control the operation of the operator position circuits.

Element AF controls the operation of the SPC on coin rating operations, element AG stores the initial period duration information, element AH stores the initial period charge information, element AJ stores the overtime period duration, element AK comprises the overtime period charge register, element AL controls the operation of the SPC on coin computations, element AM detects the end of the initial period, element AN comprises the coin call status controller program, element AP comprises the calendar which determines whether rates are to be figured on a Saturday, Sunday, holiday, or weekday basis, while element AQ comprises a time-of-day indicator.

Element AR comprises an end-of-call time and charge register, element AS comprises the end-of-call time and charge control program. Element AT comprises the portions of memory which control the operation of the scanner, element AU stores information pertaining to the communications bus translator, element AV stores information pertaining to the CPD, element AW stores information pertaining to the signal distributors, element AX analyzes the scanner answer information, element AY permits the SPC to perform the necessary checks on the input information it receives from various circuits, element AZ comprises the portion of memory which controls the operation of the teletypewriter equipment, while element BA comprises a clock which generates the necessary timing signals required by the SPC and by the various circuits of the system.

Elements BB through BE pertain to the operation of the coin tone receivers. Element BB comprises the status program, element BC the control program, element BD the translator program, and element BE the network terminal number. Elements BF through BH pertain to the announcement apparatus, with element BF comprising the status program, element BG the control program, and element BH the network terminal number.

The indicated subdivided portions of memory discussed represent only a relatively few of the many thousands of items of information and instruction that must be entered into the memory in order for the SPC to perform its required functions. The nature of these functions and their specific detail comprise no portion of the present invention and are described in detail in the aforementioned Doblmaier et al. application and the aforementioned issue of the Bell System Technical Journal pertaining exclusively to an electronically controlled switching system.

Announcement apparatus—FIGS. 14 and 15

FIGS. 14 and 15 show two different alternative embodiments of the announcement apparatus diagrammatically shown as element 152 on FIG. 1 and element 252 on FIG. 2B. The embodiment of FIG. 14 utilizes a plurality of separate prerecorded announcement tracks, each of which contains a complete message. The embodiment of FIG. 15 utilizes a plurality of prerecorded magnetic tracks, each of which contains less than a complete message. The message that is to be transmitted to a calling station by the embodiment of FIG. 15 is synthesized by connecting selected tracks in a required timed sequence to the calling connection.

Shown on FIG. 14 is the announcement equipment 1401, having a plurality of prerecorded tracks 1 through n , each of which is connected to an individual appearance on the position link by means of separate conductors 1402-1 through 1402- n . The announcement equipment is controlled in its operation by an announcement controller 1402, which is connected to the signal distributor by conductors 1403. The signals applied to this conductor by the signal distributor permit controller 1402 to control the required operations of the announcement equipment, such as for example, its starting and stopping, etc. Each of tracks 1, 2, through n , contains a complete message that is different, of course, from the message on any other track. The plurality of tracks together contain all the messages required for any possible coin call that might be served at the TSPS center. The SPC determines the particular track to which a call is to be connected, in accordance with the call information it has received and derived.

Although, normally, the message on each track would be different from that on any other track, this may not always be the case for tracks containing messages that are relatively long. It is, of course, necessary that each call be connected to a track at the time the message thereon is about to begin. Thus, in instances where a message is relatively long, in order to reduce the call waiting time, the same message would be recorded on a plurality of tracks and spaced apart timewise, so that each call requiring such a message could be connected to a track containing it with a minimum of delay.

FIG. 15 discloses announcement equipment 1501, comprising a plurality of prerecorded tracks, 1 through n , each of which is connected over individual ones of conductors 1502-1 through 1502- n to the right side of an announcement link 1503. This link comprises a switching network of the type shown for the trunk and position links on FIG. 2A. The left side of the announcement link is connected over separate conductors, 1504-1 through 1504- n , to individual appearances on the position link 204B of FIG. 2. The announcement link is controlled in its operation by controller 1505 which is connected over conductor 1506 to master scanner 236, over conductor 1507 to the central pulse distributor 232, and over conductor 1508 to the 1/N address bus 239. The starting and stopping of the recorded announcement segments is controlled by controller 1509 in response to signals received from the signal distributor over conductors 1510.

The equipment arrangement shown on FIG. 15 synthesizes each message that is transmitted to a calling station. The component parts of the message, such as syllables, words, or a plurality of words, are recorded on the different ones of tracks 1 through n . In the manner well known in the art, the link 1503 operates under control of signals received from the central pulse distributor and the 1/N address bus to connect a calling connection to the announcement tracks in a required timed sequence to synthesize the message that is to be transmitted to the calling station.

The announcement apparatus shown on FIG. 15 is connected to a call in a manner similar to that already described, namely, with reference to both FIGS. 2 and 15, a calling TSPS trunk circuit, such as for example, 203, is

connected over its T and R conductors, via the trunk and position links, to one of conductors 1504-1 through 1504-n. Let it be assumed that conductor 1504-1 is seized for this purpose. Once the connection to this conductor and the left side of announcement link 1503 is established, the SPC utilizes the call information it has stored and derived to determine the message that is to be transmitted to the calling station at this time. Accordingly, the SPC now controls the operation of link controller 1505, by means of the CPD 232 and the 1/N address bus 239, so that conductor 1504-1 is connected in a predetermined order and at predetermined times, via link 1503, to different ones of the announcement tracks 1 through n, over conductors 1502-1 through 1502-n. As already mentioned, each track contains the elemental portion of the message and the connection of conductor 1504-1 to the various tracks in sequence at the required times results in the transmission of the desired message to the calling station.

The elemental portions of the message recorded on each of tracks 1 through n may comprise portions of words, such as syllables, words, or a plurality of words. The choice of the elements to be recorded on the various tracks depends upon the number of tracks available and the number of messages required. The greater the number of tracks, the smaller may be the length of the message elements on each track, and vice versa. The announcement apparatus and the equipment associated therewith for synthesizing messages is shown diagrammatically on FIG. 15, since its details comprise no part of the present invention and since equipment for performing this function is well known in the art. For example, the conventional time-of-day announcements provided by most telephone companies is synthesized by switching a cell sequentially in a proper timed relationship between various tracks of a recorded announcement machine. Further message synthesizing equipment, operating under control of a stored program processor, is shown in the IEEE Transaction on Communication Technology, vol. 13, No. 4, December 1965, pages 395-399, in an article entitled "An Automatic Telephone Intercept System," by G. F. Abbott and R. L. Bence.

The sole function of the announcement link 1503 is to interconnect a call with the plurality of tracks required to synthesize the message that must be reproduced. Although conceptionally, this function could be performed by the switching network shown on FIG. 2A, the present disclosure shows the use of a separate link since, in many installations, the switching network on FIG. 2A might not have the capacity to perform its other functions as well as to operate at the speeds required for synthesizing the many messages required during periods of heavy coin traffic. The provision of the announcement link relieves the network of FIG. 2A from the task of synthesizing announcements and leaves it free to perform its other functions as described in the Jaejer-Joel specification.

It is to be understood that the above-described arrangements are but illustrative of the application of the principles of the invention. Numerous other arrangements may be devised by those skilled in the art without departing from the spirit and scope of the invention.

What is claimed is:

1. In a call service center having call-receiving means, means effective upon the receipt by said call-receiving means of a customer-dialed coin call for receiving calling and called station information, means for automatically driving call charge information in response to the receipt of said call information, announcement apparatus, and means responsive to the derivation of said charge information for controlling said announcement apparatus to transmit to the calling station originating said call an announcement indicating the monetary amount that is to be deposited.

2. The invention of claim 1 in combination with ap-

paratus at said calling station responsive to each coin deposited thereat for transmitting signals manifesting the amount of said deposit to said center, and means at said center responsive to the reception of said coin deposit signals for determining whether the amount deposited equals that requested by said announcement.

5 3. The invention of claim 2 in combination with a tool office connected to said center, and means responsive to a determination that the required amount has been deposited at said calling station for outpulsing call information forward to said toll office.

10 4. The invention of claim 3 in combination with means at said call service center for timing said call after the called station answers, means effective upon the termination of a predetermined call interval for controlling said announcement apparatus to transmit an announcement to said calling station indicating that said call interval has elapsed, additional means effective upon the termination of said predetermined call interval for deriving further call charge information, and means responsive to the derivation of said further information for controlling said announcement apparatus to transmit an announcement containing said further charge information to said calling station.

15 5. The invention of claim 4 in combination with means for timing the remainder of said call, means responsive to the termination of said call for computing charge information pertaining to the remainder of said call, means responsive to said computation for controlling said announcement apparatus to transmit to said calling station an announcement signifying the charges due, said coin deposit signal receiving means being effective upon the termination of said last named announcement for receiving coin deposit signals from said calling station in response to the deposit of coins thereat, and means responsive to the reception of said coin signals for determining whether the amount deposited equals that which the calling party was requested to deposit.

20 6. The invention of claim 3 in combination with means for timing said call, means responsive to the termination of said call and effective only if said call extended into overtime for computing overtime charge information, means responsive to said computation for controlling said announcement apparatus to transmit to said calling station an announcement signifying the charges due, said coin deposit signal receiving means being effective upon the termination of said last named announcement for receiving coin deposit signals from said calling station in response to the deposit of coins thereat, and means responsive to the reception of said coin signals for determining whether the amount deposited equals that which the calling party was requested to deposit.

25 7. In a call service center interconnecting a local and a toll office, a trunk circuit having an incoming end connected to said local office and an outgoing end connected to said toll office, a system controller, means responsive to the reception of a customer-dialed coin call by said trunk circuit for transmitting a call-received signal to said system controller, a switching network, a digit receiver, means effective upon the receipt of said call signal for controlling the connection of said trunk circuit via said switching network to said digit receiver, said digit receiver being effective to receive call information including calling and called station information outpulsed from said local office, means for transmitting said call information from said receiver to said controller, said switching network being effective upon the termination of local office outpulsing to disconnect said digit receiver from said trunk circuit, means including said controller responsive to the receipt of said call information from said digit receiver for deriving initial period time and charge information for said call, announcement apparatus, said network being effective upon the derivation of said initial period information for connecting said trunk circuit to said announcement apparatus, means further

responsive to the derivation of said initial period information for controlling said apparatus to transmit to the calling station originating said call in announcement signifying the initial period duration and charge, a coin signal receiver, said network being effective upon the conclusion of said announcement for disconnecting said announcement apparatus and for connecting said calling trunk circuit to said coin signal receiver, means at said calling station responsive to each coin deposit thereat for transmitting signals manifesting the amount of said deposit to said coin signal receiver, means for transmitting said deposit signals from said coin signal receiver to said system controller, and means including said system controller responsive to the receipt of said coin information for determining whether the amount deposited at the calling station equals the initial period charge specified in said announcement, said network being subsequently effective for disconnecting said calling trunk circuit from said coin tone receiver.

8. The invention of claim 7 in combination with call data outpulsing means, means responsive to a determination that the proper initial period charge was deposited for controlling said network to connect an outpulser to said calling trunk circuit, and means for controlling said outpulser to transmit call information forward to said toll office for the establishment of a connection to a called station.

9. The invention of claim 8 in combination with means effective upon an off-hook condition at said called station for monitoring and timing the initial period portion of said call, means effective upon the termination of the initial period for deriving overtime period time and charge information, said network being effective upon said last named derivation for connecting said calling trunk circuit to said announcement apparatus, and means for controlling said apparatus to transmit an announcement to said calling station signifying that the initial period has elapsed together with said overtime period time and charge information, said network being effective upon the conclusion of said announcement for disconnecting said trunk circuit from said announcement apparatus.

10. The invention of claim 9 in combination with means for monitoring and timing the remainder of said call, means effective upon the call termination for computing the chargeable overtime and the charges due thereon, said network being effective upon said computation for connecting said calling trunk circuit to said announcement apparatus, means responsive to said computation for controlling said apparatus to transmit an announcement to said calling station indicating the overtime duration and charges, said network being effective upon the termination of said announcement for disconnecting said trunk circuit from said announcement apparatus and for connecting it to said coin signal receiver, said coin signal receiver being effective for receiving and transmitting to said system controller signals indicating the monetary amount deposited at the calling station upon the call termination, and means including said system controller responsive to the receipt of said deposit signals for determining whether the overtime charges deposited equal those requested in said last named announcement.

11. In a call service center interconnecting a local and a toll office, a trunk circuit having an incoming end connected to said local office and an outgoing end connected to said toll office, a system controller, a digit receiver, means responsive to the reception of a customer-dialed coin call by said center for transmitting call information including called station information from said local office via said trunk circuit to said digit receiver, means for transmitting said call information from said

5 receiver to said controller, means including said controller responsive to the receipt of said call information for deriving charge information for said call, announcement apparatus, and means further responsive to the derivation of said charge information for controlling said apparatus to transmit via said trunk circuit to the calling station at said local office an announcement signifying the monetary amount that is to be deposited.

10 12. The invention of claim 11 in combination with a coin deposit signal receiver, means at said calling station responsive to each coin deposit thereat for transmitting signals manifesting the amount of said deposit via said trunk circuit to said signal receiver, means for transmitting said deposit signals from said receiver to said system controller, and means including said system controller responsive to the receipt of said coin deposit signals for determining whether the amount deposited at the calling station equals that requested by said announcement.

15 13. The invention of claim 12 in combination with means responsive to a determination that the amount deposited matches that requested by said announcement for controlling the completion of a connection to the called station specified by said received call information.

20 14. In a call service center interconnecting a local and a toll office, a trunk circuit having an incoming end connected to said local office and an outgoing end connected to said toll office, a system controller, means responsive to the reception of a customer-dialed coin call by said trunk circuit for transmitting a call-received signal to said system controller, a switching network, a digit receiver, means effective upon the receipt of said call signal for controlling the connection of said trunk circuit via said switching network to said digit receiver, said digit receiver being effective to receive call information 25 including calling and called station information outpulsed from said local office, means for transmitting said call information from said receiver to said controller, said switching network being effective upon the termination of local office outpulsing to disconnect said digit receiver from said trunk circuit, means including said controller responsive to the receipt of said call information from said digit receiver for deriving initial period time and charge information for said call, announcement apparatus, said network being effective upon the derivation of said initial period information for connecting said trunk circuit to said announcement apparatus, and means further responsive to the derivation of said initial period information for controlling said apparatus to transmit to the calling station originating said call an announcement 30 35 40 45 50 55 60 65 70 75 80 85 90 95 100 105 110 115 120 125 130 135 140 145 150 155 160 165
